CLAIM

The ornamental design for a vehicle cab step as shown and described.

DESCRIPTION

FIG. 1 is an isometric view of a vehicle cab step, showing an embodiment of our new design.

FIG. 2 is a front elevational view thereof.

FIG. 3 is a rear elevational view thereof.

FIG. 4 is a top plan view thereof.

FIG. 5 is a right side elevational view thereof.

FIG. 6 is an isometric view of a vehicle cab step, showing another embodiment of our new design, which is a mirror image of the vehicle cab step shown in FIGS. 1-5.

FIG. 7 is a front elevational view thereof.

FIG. 8 is a rear elevational view thereof.

FIG. 9 is a top plan view thereof; and,

FIG. 10 is a left side elevational view thereof.

The broken lines shown in the drawings depict portions of the vehicle cab step that form no part of the claimed design.

1 Claim, 8 Drawing Sheets
